[57] CLAIM

The ornamental design for a spinning toy, substantially as shown and described.

DESCRIPTION

FIG. 1 is a top perspective view of a spinning toy showing my new design;

FIG. 2 is a top plan view thereof;

FIG. 3 is a bottom plan view thereof;

FIG. 4 is a side elevational view thereof, shown on an enlarged scale; and

FIG. 5 is a cross sectional view thereof, taken along the line 5—5 of FIG. 2.
